UNITED STATES PATENT OFFICE.

HERMANN FRAHM, OF HAMBURG, GERMANY.

MEANS FOR PREVENTING THE ROLLING OF SHIPS.

968,927.

Specification of Letters Patent. Patented Aug. 30, 1910.

Application filed July 15, 1908. Serial No. 443,597.

To all whom it may concern:

Be it known that I, HERMANN FRAHM, a citizen of the free town of Hamburg, and resident of 18 Kloster Allee, of the free town 5 of Hamburg, in the German Empire, engineer, have invented certain new and useful Improvements in Means for Preventing the Rolling of Ships, of which the following is a specification:

10 This invention relates to means used for damping the rolling motion of ships by employing water tanks therein in which the periodic motion of the water when the ship rolls is utilized to counteract the rolling of 15 the ship.

It has already been proposed to counteract the rolling of ships by providing a double hull arranged so that the two walls of the hull were at a greater distance apart at 20 the bottom of the ship than at the sides. The outer hull was at the bottom provided with holes so as to place the space between the hulls in communication with the outer water. With this construction the bulk of 25 the water is arranged at the bottom of the ship and its action as regards damping the rolling motion is more in the nature of a heavy keel. The result of this is that the rolling motion is not very efficiently damped 30 but merely the period of oscillation of the ship lengthened.

According to the present invention I propose to employ tanks arranged at the sides 35 of the ship and connected to the outer water by pipes of smaller cross section than the tanks themselves. The cross section of the connection pipes is so dimensioned as to cause the periodic motion of the water in and out of the said tanks during rolling of 40 the ship to correspond as nearly as possible with the calculated periodic motion of the ship during rolling, assuming that the pressures above the water in the tanks on both sides of the vessel are maintained equal, 45 for instance by constantly exposing the water in the tanks on both sides to atmospheric pressure or in the case of closed tanks by providing for instance a cross connection between the top of the tanks. The 50 construction which I preferably employ consists of two vertical chambers arranged one at each side of the ship, said chambers communicating at their lower narrower ends with the sea water. These chambers are 55 preferably closed at their upper ends, suitable means being provided for maintaining

equal pressure above the water in opposite chambers for instance by a pipe connecting the upper ends of the chamber. In practice however owing to the well known fact that 60 each vessel develops an unforeseen rolling motion peculiar to itself and owing to the constantly varying conditions under which a vessel travels, it is found desirable to provide means for varying the lag in the flow 65 of water in the tanks or chambers. This variation may be obtained either by throttling more or less the flow of water through the connection to the sea or by varying the flow of air between the spaces above the 70 water levels in the opposite tanks or chambers. For special purposes it is sometimes necessary to get the water levels in both tanks into a different height in relation to the outer sea. A suitable device for this is 75 to control the degree of pressure or vacuum above the water levels in the chambers and a simple method is to connect the cross air pipe with a pressure or vacuum pipe.

The invention will be more readily understood from the following description of 80 the apparatus illustrated in the accompanying drawing which is a diagrammatic cross section through a ship provided with anti-rolling chambers according to the present 85 invention.

In the drawing the chambers *m* and *n* on each side of the ship are connected by pipes *t* and *r* respectively with the water in which the vessel is floating. The chambers are 90 shown as provided with tapering sides which has the effect of enabling the period of the oscillations to be regulated in a manner described in a co-pending patent application, filed by me. The opening to the sea water is 95 also tapered at *s* to prevent shocks or undue friction. The upper ends of the vessels *m* and *n* are connected by means of a pipe *o*² in which a valve *o*³ is arranged to effect throttling to control to some extent the period of oscillation of the water in and out of 100 the chambers *m* and *n*. As can be seen from the figure the outer water is higher than the water in the vessels during the normal position of the ship and in consequence 105 the air in the vessels *m* and *n* is in this case subjected to an initial pressure equal to the head of water *p*. It will also be seen that in this case the quantities of water are alternately greater on each side during rolling of 110 the boat. During rolling the transference of the bulk of the weight from one side of

the boat to the other takes place periodically out of phase with the rolling of the boat. There are thus two periodic motions set against one another and thereby a balancing effect is obtained.

I claim:

1. Apparatus for damping the rolling motion of ships having within the ship, a vertical chamber at each side of the ship, 10 said chambers being widened upwardly and connections from the bottom end of each of said chambers to the sea water, said chambers and connections being so dimensioned that the periodic oscillations of water in and 15 out of said vertical chambers are substantially equal to the natural period of oscillations of the ship.

2. Apparatus for damping the rolling motion of ships having within the ship, a 20 vertical chamber at each side of the ship, said chambers being closed at their upper ends, connections from each of said chambers to the sea water, said connections and chambers being so proportioned that the 25 period of oscillation of the water in and out of the chambers is substantially equal to the natural period of oscillation of the ship, and means for regulating the degree of vacuum or pressure in the upper ends of said 30 vertical chambers.

3. Apparatus for damping the rolling motion of ships having within the ship, a

vertical chamber at each side of the ship, 35 said chambers being closed at their upper ends, connections from each of said chambers to the sea water, said connections and the chambers being so proportioned that the period of oscillation of the water in and out of the chambers is substantially equal to the natural period of oscillation of the ship, a 40 pipe joining the upper ends of the vertical chambers on each side of the ship and a valve in said pipe.

4. Apparatus for damping the rolling motion of ships having within the ship a 45 vertical chamber at each side of the ship, said chambers being widened upwardly and closed at their upper ends, connections from the bottom end of each of said chambers to the sea water, said chambers and connections being so dimensioned that the period of oscillation of water in and out of said vertical chambers is substantially equal to the natural period of oscillation of the ship, a pipe joining the upper ends of the 50 vertical chambers at each side of the ship and a valve in said pipe.

In witness whereof I have hereunto set my hand in the presence of two witnesses.

HERMANN FRAHM.
